US0D1027342S

(12) **United States Design Patent** (10) **Patent No.:** **US D1,027,342 S**
(45) **Date of Patent:** **** May 14, 2024**

(54) **SWIMMING POOL CLEANER ROBOT**

(71) Applicant: **Poolelf Smart Technology Co., Ltd.,**
Huai'an (CN)

(72) Inventor: **Xin Cao**, Ningbo (CN)

(73) Assignee: **Poolelf Smart Technology Co., Ltd.,**
Huai'an (CN)

(**) Term: **15 Years**

(21) Appl. No.: **29/835,497**

(22) Filed: **Apr. 19, 2022**

(51) LOC (14) Cl. **15-05**

(52) U.S. Cl.

USPC **D32/15**

(57) **CLAIM**

The ornamental design for a swimming pool cleaner robot, as shown and described.

DESCRIPTION

FIG. 1 is a perspective view of a swimming pool cleaner robot, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the swimming pool cleaner robot that form no part of the claimed design.

1 Claim, 8 Drawing Sheets
